UNITED STATES PATENT OFFICE

2,166,243

BOBBIN

William J. Elvin, Cumberland, Md., assignor to
Celanese Corporation of America, a corpora-
tion of Delaware

Application December 17, 1937, Serial No. 130,275

2 Claims. (Cl. 242—118)

This invention relates to improvements in bobbins, spools and like yarn holders employed in textile industries, and relates more particularly to bobbins, spools and the like adapted for use in spinning and twisting devices.

It is an object of this invention to provide bobbins or spools with braking surfaces.

Another object of this invention is the provision on one end of a bobbin or spool of an extended bushing adapted to provide a surface for braking, or stopping the rotation of the bobbin or spool on a rotating spindle.

A further object of this invention is to provide the extended bushing of the bobbin or spool with a braking surface which, with a suitable brake band or tape, furnishes the desired yarn tension when unwinding by unrolling the bobbin or spool as a source of supply in textile operations subsequent to the spinning or twisting.

Other objects of this invention, together with certain details of construction and combinations of parts, will be described more particularly in the following specification and pointed out in the appended claims.

25 In the drawing:

Fig. 1 is a side elevational view, partly in section, of one form of this invention;

Fig. 2 is a view of one end, partly in section, of the bobbin or spool shown in Fig. 1 showing the means for furnishing the tension on the yarn as it is unwound from the bobbin or spool;

Fig. 3 is a side elevational view, partly in section, of another form of this invention, and

Fig. 4 is a view of one end of the bobbin or spool shown in Fig. 3.

Like characters of reference indicate like parts throughout the several views of the drawing.

Referring to the drawing wherein the preferred embodiments of this invention are set forth, the reference numeral 5 generally indicates a bobbin or spool commonly made by turning the same from a solid block of wood and the like, but which may also be made by molding the same from any suitable molding materials such as, for example, 40 resins, thermoplastic derivatives of cellulose such as cellulose acetate, and other plastic moldable substances or compositions. The bobbin or spool 5 comprises flanges 6 and 7 generally formed integral with the core or barrel 8 upon which the 45 yarn is adapted to be wound.

In accordance with this invention, the bore 9 at the top end of the barrel 8 is enlarged as shown at 11 to receive, as with a force fit, the shank 12 of a bushing generally indicated by the reference numeral 13. This bushing may be made of any

suitable material such as wood, metal, or plastic molding compositions. The bushing is provided with a portion integral with the shank 12 and which extends beyond the end of the bobbin or spool. The portion of the bushing external to 5 the bore of the bobbin or spool is adapted to act as a braking surface. This external portion comprises two spaced flanges 14 and 15 forming between them a groove 16, the purpose of which will hereinafter be set forth. The flange 15 is 10 adapted to rest on the upper or outer surface of flange 6, and the flange 14 is provided with an annular groove 17, which groove 17 is adapted to receive annular rings for identifying the quality, 15 denier, twist and filament count of the yarn wound on the bobbin or spool.

The bore 18 of the bushing may extend through the top of the flange 14 as shown in the Figs. 1 and 2, or the bore of the bushing may be closed at this end as shown in the modification illus- 20 trated in Figs. 3 and 4.

The external portion of the bushing 13 performs a dual braking function. Thus, when the bobbin or spool is rotating on the spindle of the spinning or twisting device, the rotation of said 25 bobbin or spool may be stopped by an operative by grasping the external portion with his hand. In Fig. 2, there is shown means for applying tension on the yarn as it is being unwound by unrolling from the bobbin or spool. The tension 30 applying means comprises a brake band or tape 19 carried in groove 16. One end of the brake band or tape 19 is fixed to a suitable part of the device (not shown) for holding the bobbin or spool while it is being unwound. The free end 35 of brake band or tape 19 is adapted to support an interchangeable weight 22, the size of the weight depending upon the amount of tension desired to be put on the yarn being unwound.

It is to be understood that the foregoing de- 40 tails description is given merely by way of illustration and that many variations may be made therein without departing from the spirit of my invention.

Having described my invention what I desire to 45 secure by Letters Patent is:

1. In a bobbin or spool for use in spinning and twisting machines, a bushing comprising a shank adapted to be received in the bore of the bobbin or spool, and having a portion integral with said shank and extending beyond the end of said bobbin or spool, said extended portion having spaced flanges thereon forming a plurality of braking surfaces, one of said braking surfaces being adapted to receive a brake band.

2. In a bobbin or spool for use in spinning and twisting machines, a bushing comprising a shank adapted to be received in the bore of the bobbin or spool, and having a portion integral with said shank and extending beyond the end of said bobbin or spool, said extended portion having spaced

flanges forming a groove therebetween, said groove being adapted to receive a brake band and to function as a braking surface for said brake band when the yarn is being unwound therefrom.

WILLIAM J. ELVIN.
